(57) **CLAIM**

The ornamental design for fringing on side panels of a portable shelter canopy as shown and described.

DESCRIPTION

FIG. 1 is an upper perspective view of a first embodiment of the fringing on side panels of a portable shelter canopy design according to my invention;

FIG. 2 is a right side elevational view of the fringing on side panels of a portable shelter canopy shown in FIG. 1;

FIG. 3 is a left side elevational view of the fringing on side panels of a portable shelter canopy shown in FIG. 1;

FIG. 4 is a top plan view of the fringing on side panels of a portable shelter canopy shown in FIG. 1;

FIG. 5 is a bottom plan view of the fringing on side panels of a portable shelter canopy shown in FIG. 1;

FIG. 6 is a front elevational view of the fringing on side panels of a portable shelter canopy shown in FIG. 1;

FIG. 7 is a rear elevational view of the fringing on side panels of a portable shelter canopy shown in FIG. 1;

FIG. 8 is a lower perspective view of the fringing on side panels of a portable shelter canopy shown in FIG. 1;

FIG. 9 is an upper perspective view of a second embodiment of the fringing on side panels of a portable shelter canopy design according to my invention;

FIG. 10 is a right side elevational view of the fringing on side panels of a portable shelter canopy shown in FIG. 9;

FIG. 11 is a left side elevational view of the fringing on side panels of a portable shelter canopy shown in FIG. 9;

FIG. 12 is a top plan view of the fringing on side panels of a portable shelter canopy shown in FIG. 9;

FIG. 13 is a bottom plan view of the fringing on side panels of a portable shelter canopy shown in FIG. 9;

FIG. 14 is a front elevational view of the fringing on side panels of a portable shelter canopy shown in FIG. 9;

FIG. 15 is a rear elevational view of the fringing on side panels of a portable shelter canopy shown in FIG. 9; and,

FIG. 16 is a lower perspective view of the fringing on side panels of a portable shelter canopy shown in FIG. 9.

(Continued)

The evenly spaced broken lines shown in the drawings depict portions of the fringing on side panels of a portable shelter canopy that form no part of the claimed design.
